Daniel P. Whelan, Merrick, N. Y.

Application October 28, 1938, Serial No. 80,729

Term of patent 14 years

To all whom it may concern:

Be it known that I, Daniel P. Whelan, a citizen of the United States, residing at Merrick, county of Nassau, State of New York, have invented a new, original, and ornamental Design for a Transparent Bar, of which the following is a specification, reference being had to the accompanying drawing forming a part thereof, and in which

Fig. 1 is a perspective view of a transparent bar embodying my new design;

Fig. 2 is a top plan view of the transparent bar:
and

Fig. 3 is an end view thereof.

I claim:

The ornamental design for a transparent bar,
as shown.

DANIEL P. WHELAN.
